UNITED STATES PATENT OFFICE

2,627,853

TOY TORPEDO LAUNCHER

Edward W. Koepnick, Dayton, Ohio

Application October 18, 1947, Serial No. 780,650

3 Claims. (Cl. 124—26)

1

This invention relates to a toy torpedo launcher and more particularly to a catapult simulating a toy submarine ejecting a torpedo. This application is a continuation in part of my copending application Serial No. 627,252, filed November 7, 1945, and now abandoned.

An object of this invention is to provide a catapult for projecting a missile towards a toy battleship.

Another object of this invention is to provide a toy torpedo launcher in which the parts may be manufactured cheaply and in which the cost of assembling the parts is maintained at a minimum.

Another object of this invention is to provide an improved arrangement for supporting the coil spring elements in a toy torpedo launcher.

Still another object of this invention is to provide an improved sear arrangement which eliminates the need for accurately machining the parts and which provides for a more positive engagement between the sear and the torpedo.

Other objects and advantages reside in the construction of parts, the combination thereof and the mode of operation, as will become more apparent from the following description.

Figure 1 is a plan view showing a preferred form of torpedo launcher.

Figure 2 is a vertical sectional view taken along the central longitudinal axis of Figure 1;

Figure 3 is a plan view of the lower half of the torpedo launcher.

Figure 4 is a plan view showing the bottom side of the top half of the torpedo launcher;

Figure 5 is a sectional view taken on line 5—5 of Figure 1; and

Figure 6 is a fragmentary sectional view taken on line 6—6 of Figure 3.

In Figures 1 through 6, I have shown an arrangement for a torpedo launcher in which the plastic parts forming the main submarine body are so constructed and arranged as to reduce the cost of the earlier types of launchers both by reducing the amount of plastic required and by making other improvements which simplify the assembly of the parts and at the same time improve the operation of the torpedo launching mechanism. In this embodiment the submarine proper comprises an upper molded plastic member 202 and a lower molded plastic member 204.

Whereas the submarines disclosed in said copending application comprise substantially solid pieces of molded material the elements 202 and 204 have been designed so as to reduce the amount of plastic required and to reduce the

2

weight of the unit. In order to provide a central hollow tube portion for supporting the torpedo 90 and the torpedo propelling spring 208 there is provided a centrally disposed semi-tubular portion 210 in the lower member 204 and a somewhat similar semi-tubular portion 212 in the upper member 202. A plurality of reinforcing ribs 214 have been provided as shown which serve to prevent buckling of the outer walls of the submarine and serve to hold the centrally disposed tubular portions in place. As indicated in Figures 2, 3, and 4, the one end of the spring 208 is provided with a hook which is held in place within the groove 216 formed between the meeting edges of the pieces 202 and 204.

A sear 220 is pivotally mounted on a metal pin 222 the ends of which are held in place within opposed recesses provided in the plastic members 202 and 204 such as the one recess 224 shown in Figure 4. The sear 220 includes a first projection 226 which is adapted to engage within the annular recess 92 provided in the torpedo or missile 90. It will be noted that the projection 226 engages the wall of the recess 92 at such an angle and from such a direction that jarring of the parts or any increase in the spring pressure tending to force the missile 90 outwardly tends to increase the force with which the sear engages the wall of the groove 92. This construction represents a definite improvement over the construction shown in said copending application. In the arrangement shown in said copending application, the torpedo engaging sear or pawl tends sooner or later to produce rounded corners on the torpedo and also the sear with the result that after repeated use the sear fails to hold the torpedo in place.

The sear is provided with a second and rounded projection 228 which registers within the slot 230 provided in the end of the pivoted trigger member 232. The trigger 232 is pivotally supported on a metal pin 234 supported between the plastic elements 202 and 204. A coil spring 236 which is mounted in a cavity 238 formed in the meeting edges of the plastic members 202 and 204 biases the trigger element 232 and the sear element 220 into the torpedo holding position.

The above described parts are easily assembled and do not require the use of any screws for holding them in place. The elements 208, 220, 222, 232, 234 and 236 are laid in place on the lower plastic member 204 and then the upper piece 202 is laid on top and the elements 202 and 204 are bonded together so as to form a unitary mounting for the torpedo launching elements.

Any well known type of bonding material may be used and the type of bonding material used depends partly upon the type of plastic used. It will be noted that the lower element 204 is provided with a plurality of integrally formed alignment pins 240 which engage within complementary recesses 242 provided in the upper member 202. The construction and arrangement of the molded elements is such that they may be made in the simplest form of molds and once the parts are assembled they form a neat and sturdy unit.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A toy torpedo launching device comprising in combination, a first molded plastic element simulating the lower half of a submarine and having a semi-circular channel formed in its upper surface extending substantially along the longitudinal axis of the element, a second molded plastic element simulating the upper half of a submarine and having a semi-circular channel in its lower side complementary to said first named semi-circular channel and forming with said first named channel a torpedo tube, a sear, means pivotally supporting said sear adjacent said tube with a portion of the sear adapted to project into said tube for engagement with a toy torpedo, a trigger element pivotally supported between said molded elements and having one end arranged in engagement with said sear and having its other end projecting to the outside of said submarine, and a spring disposed within said tube and having an end held within a recess formed in one of said plastic elements, said means for pivotally supporting said sear being located forwardly from the point of contact between the sear and the torpedo.

2. A toy submarine having a first molded plastic shell member, said first shell member including transversely extending reinforcing ribs, a second molded plastic shell member secured to said first named shell member, said first and second named shell members having formed integrally therewith a torpedo launching tube, a compression spring disposed within said tube and having one end anchored within said tube and having the other end arranged for engagement with a toy torpedo, and trigger mechanism for controlling the release of a toy torpedo, said trigger mechanism being movably mounted on and between said first and second named shell

members, said trigger mechanism comprising a trigger element and a pivoted sear, said sear having a first projection for engaging said toy torpedo and having a second projection arranged in registry with a portion of said trigger, a first pivot for said sear, a second pivot for said trigger element, said first projection on said sear being arranged between said first and second pivots.

10 3. A toy submarine having a first molded plastic shell member, said first shell member including transversely extending reinforcing ribs, a second molded plastic shell member secured to said first named shell member, said first and second named shell members having formed integrally therewith a torpedo launching tube, a compression spring disposed within said tube and having one end anchored within said tube and having the other end arranged for engagement with a toy torpedo, and trigger mechanism for controlling the release of a toy torpedo, said trigger mechanism being movably mounted on and between said first and second named shell members, said trigger mechanism comprising a trigger element and a pivoted sear, a second compression spring carried by and between said shell members urging said sear into latching engagement with the torpedo, said sear having a first projection for engaging said toy torpedo and having a second projection arranged in registry with a portion of said trigger, a first pivot for said sear, a second pivot for said trigger element, said first projection on said sear being arranged between said first and second pivots whereby the resultant force of said first compression spring acting through the torpedo urges said sear in the direction toward the axis of the torpedo so as to more firmly engage the torpedo.
